BAND-SPREAD TUNING CIRCUIT FOR
RADIO RECEIVERS

Frank Caplin, Bournemouth, and Charles Edward
Payne, Mitcham, England, assignors to Radio
Corporation of America, New York, N. Y., a
corporation of New York

Application June 24, 1941, Serial No. 399,436
In Great Britain July 9, 1940

14 Claims. (Cl. 250—40)

The present invention relates to tuning circuits for radio receivers and is more particularly concerned with tuning circuits employed for band-spreading purposes.

Band-spread tuning circuits are well-known but the majority suffer from serious disadvantages due partly to the difficulty of combining the feature of band-spreading with the feature of wide tuning range. For instance in the known arrangement where a small capacity "trimmer" condenser is connected in parallel with each tuning condenser, the degree of band-spreading varies as the third power of the frequency and hence the degree of band-spreading is very different at the two ends of the tuning range. Band-spreading by means of an auxiliary variable condenser in series with the main tuning condenser has also been proposed but it is found that it is unsuitable where the total tuning range or the tuning range for any one wave-band is wide.

It has also been proposed to band-spread by effecting small variations in the tuning inductance but, while this method overcomes the above disadvantage, mechanical difficulties arise when it is employed in a receiver arranged to operate on a plurality of wavebands.

It is an object of the present invention to provide a tuning circuit employed for band-spreading purposes which does not suffer from the above disadvantage and which does not involve any complex mechanical mechanism in its application.

According to the invention band-spreading is effected by a variable inductance which is not part of the tuning circuit proper but is caused to influence tuning by its effect on an inductance which is connected in parallel with the variable inductance and is adapted either to be coupled by a mutual-inductance coupling to the tuning coil or to be formed by part or all of the tuning coil itself.

With this arrangement the degree of band-spread is constant for each waveband and by employing a plurality of coupling circuits which may be switched in as desired, the circuit is easily applicable to a receiver which is arranged to operate over a number of wavebands.

While the degree of band-spread is constant for each waveband, it varies with frequency within any waveband and it is a further object of the invention to provide an arrangement in which the degree of band-spread is independent of frequency.

According to this feature of the invention the variable inductance forms part of a resonant cir-

cuit, the resonant frequency of which is below the lowest frequency in the waveband.

The invention will be better understood by the following description taken in conjunction with the accompanying drawings in which

Fig. 1 shows the tuning circuit in its simplest form;

Fig. 2 shows a curve giving the change in frequency over any waveband when employing the circuit of Fig. 1;

Fig. 3 shows the circuit of Fig. 1 applied to a receiver having two tuned circuits;

Fig. 4 shows a second embodiment of the invention in its simplest form;

Fig. 5 shows a curve showing the same relation as the curve of Fig. 2 but for the circuit of Fig. 4;

Fig. 6 shows the invention applied to the case where two wavebands are band-spread while

Fig. 7 shows the invention applied to the case where two tuned circuits are employed and band-spread tuning is employed over two wavebands;

Figs. 8, 9, 10 and 11 show four mechanical arrangements for effecting the desired variation in the band-spread inductance.

Referring now to Fig. 1 of the drawings the tuning condenser is indicated by C and the tuning inductance by L₁. The band-spread variable inductance L is coupled to the tuning circuit proper by means of the inductance L₂ in parallel therewith and mutually coupled to the tuning inductance L₁. It will be seen that the current in the variable inductance and consequently its effect on the main tuning inductance L₁ decreases with increasing frequency and thus the advantage of employing a variable inductance as against a variable capacity for band-spreading is obtained and by employing a plurality of mutual inductances which may be switched in as desired the arrangement is easily applicable to a receiver

capable of receiving signals over a number of wavebands. It will also be appreciated that the invention may be applied to each of a plurality of tuned circuits, for instance different stages in a receiver, by providing a plurality of matched variable inductances ganged together mechanically, one for each circuit and each associated with an appropriate coupling circuit and tuning coil as shown in Figure 3.

It will be seen from the curve shown in Fig. 2 where band-spread af is plotted against frequency for the circuit of Fig. 1 that the band-spread changes with frequency and is in fact proportional to the frequency. In Fig. 2 the band-spread tuning range is from f min. to f max. This is a

disadvantage from the point of view of conven-

ience of operation and calibration and can be avoided by employing the circuit shown in Fig. 4 where a condenser C_1 is inserted between the variable inductance L and the coupling inductance L_s , the value of the condenser being such that the resonant frequency of the circuit L, L_s, C_1 is below the lowest frequency in the waveband as shown in the curve of Fig. 5. From this curve it will be seen that between the frequency $f_{\text{min.}}$ and $f_{\text{max.}}$ the degree of band-spread has a substantially constant value, the deviation from this value at the centre of the band being quite small.

Fig. 6 shows a tuning arrangement for a receiver having two wavebands. Two coupling circuits formed of mutually coupled inductances L_1, L_3 and L_2, L_4 are provided and are arranged to be connected alternatively between the main tuning condenser C and the variable band-spread inductance L by means of a two position switch having two switch arms S_1 and S_2 . If the ratio between the inductances L_1, L_3 and L_2, L_4 is the same then the degree of band-spread will be constant over each waveband. Fig. 7 shows an arrangement for band-spread tuning over two wavebands in a receiver having two tuning circuits.

In Fig. 6, the condensers C_1 and C_2 may be inserted if it is required to render the band-spread substantially independent of frequency over both the wavebands as explained above.

In the arrangements shown in Figs. 8 and 10 in which similar references indicate similar parts the variable band-spread inductance L is wound on a suitable former 10 which is attached to a plate 13 which with the box 14 may form part of the screening arrangement of the receiver. A high frequency iron core 11 is mounted on a spindle 12 which is adapted to be moved so that the core travels into or out of the inductance coil L . A spring 15 is provided, one end of which is fixed to the plate 13 while the other is fixed to the spindle 12 so that the tendency is for the core to be moved out of the inductance coil. The movement of the spindle may be controlled as shown in Fig. 8 by an arrangement acting on the principle of the Archimedean screw. The spindle 12 is provided with a stud 16 resting on curved surface 17 of such a shape that on rotation by the knob 18 of the spindle 18 on which the surface 17 is fixed causes a longitudinal movement of the spindle 12. It will be understood that by suitably choosing the dimension of the surface 17 a very fine movement of the spindle 12 may be obtained. It will be understood that a plurality of such units may be mounted on the spindle 12 as shown in Fig. 9.

In Fig. 10 the movement of the spindle 12 is derived from a shaft 27 arranged at right angles thereto. A cam 26 is mounted on the shaft 27 and the cam engages with a roller 28 mounted on the spindle 12. Rotation of the shaft 27 thus causes the spindle 12 to move longitudinally and the core 11 to move into or out of the inductance coil L . It will be appreciated that with this arrangement several cams may be mounted on the shaft 27 so that ganged control of a number of stages of the receiver is obtained as shown in Fig. 11.

We claim:

1. A band-spread tuning arrangement for radio receivers comprising a main tuning circuit having a tuning inductance, a variable band-spread inductance separate from said tuning circuit, and means for coupling said variable band-spread in-

ductance to said tuning inductance whereby variation of said variable band-spread inductance has the effect of varying the tuning of the main tuning circuit due to the effect of said band-spread inductance on said coupling means.

2. A band-spread tuning arrangement for radio receivers comprising a main tuning circuit, a variable band-spread inductance separate from said tuning circuit, a second inductance connected in parallel with said variable band-spread inductance, and means for coupling said second inductance to said tuning circuit whereby variation of said variable band-spread inductance has the effect of varying the tuning of the main tuning circuit due to the effect of said band-spread inductance on said second inductance.

3. A band-spread tuning arrangement for radio receivers comprising a main tuning circuit, a band-spread inductance separate from said tuning circuit, means comprising a movable core for varying said band-spread inductance, and means for coupling said band-spread inductance to said tuning circuit whereby variation of said variable band-spread inductance has the effect of varying the tuning of the main tuning circuit due to the effect of said band-spread inductance on said coupling means.

4. A band-spread tuning arrangement as claimed in claim 3 wherein the said movable core is composed of high frequency iron.

5. A band-spread tuning arrangement for radio receivers arranged to operate over a plurality of wave-bands and comprising a tuning circuit, a plurality of tuning inductances for said tuning circuit, a variable band-spread inductance, a plurality of coupling inductances for coupling said variable band-spread inductance to said tuning circuit, each of said coupling inductances being mutually coupled to one of said tuning inductances, switch means for connecting said variable band-spread inductance to any one of said coupling inductances and switch means for connecting any one of said tuning inductances to said tuning circuit.

6. A band-spread tuning arrangement for radio receivers comprising a main tuning circuit, a resonant circuit the resonant frequency of which is below the lowest frequency in the waveband, a variable band-spread inductance forming part of said resonant circuit, and a second inductance connected in parallel with said variable band-spread inductance and coupled to said tuning circuit.

7. A band-spread tuning arrangement for radio receivers arranged to operate over a plurality of wavebands and comprising a tuning circuit, a plurality of tuning inductances for said tuning circuit, a plurality of resonant circuits one for each wave-band and having a resonant frequency which is below the lowest frequency in the waveband with which it is associated, a variable band-spread inductance forming a common part of all said resonant circuits, a plurality of coupling inductances, each of which is mutually coupled to one of said tuning inductances, switch means for connecting said variable band-spread inductance to any one of said resonant circuits by way of one of said coupling inductances, and switch means for connecting any one of said tuning inductances to said tuning circuit.

8. A band-spread tuning arrangement for a radio receiver comprising at least one tunable circuit provided with a fixed inductance and a shunt variable tuning condenser for tuning the circuit over a comparatively wide frequency

range, and an auxiliary circuit comprising a variable band-spread inductance and a shunt inductance which is mutually coupled to the fixed inductance of the tunable circuit, the arrangement being such that adjustment of the band-spread inductance has the effect of varying the tuning of the tunable circuit over a comparatively narrow frequency range.

9. A band-spread tuning arrangement for a radio receiver comprising at least one tunable circuit provided with a fixed inductance and a shunt variable tuning condenser for tuning the circuit over a comparatively wide frequency range, an auxiliary circuit comprising a band-spread movable core inductance and a shunt inductance which is mutually coupled to the fixed inductance of the tunable circuit, and means for moving the core to effect adjustment of the band-spread inductance and coincidentally the tuning of the tunable circuit over a comparatively narrow frequency range.

10. A band-spread tuning arrangement for a multi-band radio receiver comprising at least one tunable circuit for each band provided with a fixed inductance and a shunt variable tuning condenser for tuning each of said circuits over a comparatively wide frequency range in its respective band, and an auxiliary circuit for each band comprising a variable band-spread inductance and a shunt inductance which is mutually coupled to a corresponding fixed inductance of one of the tunable circuits, the arrangement being such that adjustment of the band-spread inductance has the effect of varying the tuning of each tunable circuit over a comparatively narrow frequency range in its respective band.

11. A band-spread tuning arrangement for a multi-band radio receiver comprising a fixed in-

ductance for each band, a variable tuning condenser and means for selectively shunting said condenser across one of the fixed inductances to form a circuit which is tunable over one of the bands, a second fixed inductance for each band mutually coupled to the corresponding fixed inductance of the tunable circuit, a variable band-spread inductance and means for selectively shunting said band-spread inductance across one of the second fixed inductances.

12. A band-spread tuning arrangement in accordance with the invention defined in claim 11 wherein the selective shunting means are constituted by switches which are controlled in unison.

13. A band-spread tuning arrangement for a multi-band radio receiver comprising a plurality of high frequency transformers corresponding to the number of bands, a variable tuning condenser, means for selectively connecting the tuning condenser in shunt across the primary of either transformer whereby the resulting circuit is tunable over a comparatively wide frequency range in its respective band, a variable band-spread inductance, means for selectively connecting said inductance in shunt across the secondary of either transformer whereby adjustment of the band-spread inductance has the effect of varying the tuning of either tunable circuit over a comparatively narrow frequency range in its respective band.

14. A band-spread tuning arrangement in accordance with the invention defined in claim 13 wherein the selective connecting means are constituted by switches which are controlled in unison.
